UNITED STATES PATENT OFFICE.

ALBERT SICHEL, OF NEW YORK, N. Y.

MANUFACTURE OF METALLIC CAPSULES.

SPECIFICATION forming part of Letters Patent No. 257,090, dated April 25, 1882.

Application filed November 30, 1881. (No model.)

To all whom it may concern:

Be it known that I, ALBERT SICHEL, of the city, county, and State of New York, have invented a certain new and useful Improvement 5 in the Manufacture of Metallic Capsules, of which the following is a specification.

Metallic capsules are made usually from soft or ductile metal—such, for instance, as tin-foil, or foil produced by rolling into sheets of 10 proper thickness ingots having a lead core and tin exterior.

I remark at the outset that it is essential that capsules should have slightly-tapered sides, to enable them to be easily fitted upon the necks 15 of bottles, &c., and also to permit them to be nested and brought compactly within small compass for shipment and transportation.

It has been customary heretofore, so far as I am aware, to produce metallic capsules of 20 this kind in one of three ways. They have been spun on a lathe; but this process is slow and expensive as well. They have also been produced by a punching operation; but this mode of making them is disadvantageous, in 25asmuch as only shallow caps—say not exceeding three-eighths to one-half of an inch deep—can thereby be produced, and the caps are defective in that their sides are considerably thinner than their tops or ends. By still another 30 method they have been produced by the successive action of a series of dies and punches; but this method is complicated and troublesome, requiring, as it does, the employment of a number of interdependent dies and punches. 35 The machinery, moreover, is very expensive, and much time is consumed in setting and adjusting the dies.

It is my object to produce tapered metallic capsules in a simpler, more effective, and more 40 economical way than is practicable under either of the above-mentioned methods.

To this end I have devised an improvement in the art of manufacturing metallic capsules which involves two steps. The first step is to 45 form a cylindrical or straight-sided cap-blank from a disk or blank of foil material by the joint action of a die in which the disk is placed and a cylindrical plunger brought forcibly to bear upon that disk with the effect of squeezing out a portion of the metal so that it shall 50 run up between the sides of the die and plun-

ger, and thus form the cylindrical portion of the cap. In this way, without drawing or punching the soft metal, I produce by one manipulation a cylindrical cap-blank. The next 55 step is to convert the cap from the cylindrical to the conical or tapering form by forcing it down into a die of the proper taper by means of a plunger having a taper corresponding to that of the die. By these two successive steps I can produce a long tapering capsule in which the metal is distributed so that the sides and top or end shall be practically of the same thickness. The mechanism employed is inexpensive and free from complication, and the capsules can be made rapidly 65 and economically.

My improvement will be readily understood by reference to the accompanying drawings, in which I have represented so much of the 70 machinery employed as needed for the purpose of explaining my invention.

In Figure 1 is represented diagrammatically in section the cylindrical die B and cylindrical plunger A, used to produce the cylindrical or 75 straight-sided cap.

In Fig. 2 is shown at C, in plan and side elevation, the soft-metal disk or blank to be acted on. This disk is placed in the die, and the plunger is then brought down upon it with 80 force. The effect will be to squeeze out from beneath the plunger a portion of the metal which will run up between the sides of the plunger and die, and upon the plunger, so as to form a straight-sided or cylindrical cap, as indicated at C', Fig. 1. The plunger is then lifted and the cylindrical cap stripped from it. The latter is shown separately in side elevation at C', Fig. 3. Its open end is as large, or nearly as large, in diameter as is required for the open 90 end of the tapered finished cap. I then give the cylindrical cap C' the requisite taper by forcing it down in a tapering die, D, (shown diagrammatically in connection with its plunger E in Fig. 4.) The mouth or open end of the die is 95 about of the diameter of the top or closed end of the cap C'. It thence gradually decreases in diameter downward until it is of a size to fit snugly around the spring-upheld follower D', which forms the bottom of the die. That 100 portion of the plunger E which enters the die is of a size and taper to fit the die, its lower

end being of the same size as the upper end of follower D'. The cap C' is placed open end upward in the die D, resting on the end of follower D', and the plunger E is then brought 5 down, so as to enter the cap and clamp it upon the head of the follower, as indicated in Fig. 4. The plunger continues to descend until it is forced home in the die, pushing before it the follower D' against the stress of its spring D².
10 By the action of these devices the diameter of the head or closed end of the capsule is decreased, and its sides are tapered and slightly elongated, as indicated in Fig. 4 at C². This operation concludes the process, and the capsule when removed will have the form shown 15 at C² in Fig. 5, which is a side elevation of the completed article.

Having described my invention, what I claim, and desire to secure by Letters Patent,
20 is—

The improvement in the art of manufacturing metallic capsules, which consists in first producing a cylindrical cap from a soft-metal blank by the conjoint action of a die and plunger, by which the disk is pressed or squeezed, 25 substantially in the manner described, and then subjecting this cap to the action of a tapering die and plunger, by which said cap is pressed into the form of a tapering capsule, substantially as and for the purposes hereinbefore set 30 forth.

In testimony whereof I have hereunto set my hand this 28th day of November, 1881.

ALBERT SICHEL.
